UNITED STATES PATENT OFFICE.

EMMANUEL W. ROBINSON, OF CAMP LEWIS, WASHINGTON.

WINDOW-JACK.

1,330,348.

Specification of Letters Patent. Patented Feb. 10, 1920.

Application filed January 2, 1919. Serial No. 269,317.

To all whom it may concern:

Be it known that I, EMMANUEL W. ROBINSON, a citizen of the United States, and resident of Camp Lewis, county of Pierce, 5 and State of Washington, have invented certain new and useful Improvements in Window-Jacks, of which the following is a specification.

My invention relates to means employed 10 for raising and lowering windows, and consists of what may be called a jack, which is entirely separable from the window, and in fact has no connection therewith except while being used, and which may be employed 15 plowed to raise or close it as may be desired.

The object of my invention is to provide a tool of moderate size which may be used for raising and lowering windows where they are difficult to move, as for instance, 20 the windows in cars.

My invention consists of the novel parts and combinations of parts which will be herein described and then particularly defined in the claims. The accompanying 25 drawings show my invention embodied in the types of construction which I now prefer to use.

Figure 1 is a side view of my device shown applied to a window.

Fig. 2 is a side view of the same device taken, however, from a point at right angles to that of Fig. 1.

Fig. 3 is a section on the line 3—3 of Fig. 2.

Fig. 4 shows, in detail, the construction of the hook by which engagement is made with the window.

Figs. 5 and 6 are, respectively, cross section and side elevation, of the dog and its 40 operating mechanism which is used to connect the two parts of the jack frame.

Fig. 7 is an edge view, and Fig. 8 a side view, of the operating part of a modified type of construction.

Fig. 9 is a cross section taken on the line 45 9—9 of Fig. 7.

It is very common to find windows which are very difficult to open or close and this often produces considerable trouble. The 50 object of my invention is to provide a device which may be applied to a window to raise or to lower it when it sticks and cannot be raised or lowered by hand.

I provide a small jack which is provided

with means by which it may be enabled to 55 engage the window and power be applied to raise it. I will first describe the type of construction illustrated in Figs. 1 to 6 inclusive.

The frame of the device consists of two 60 parts, 1 and 2. The part 1 is the main portion of the frame. The part 2 is a bar which is mounted to slide upon the other part, the two thus acting in a telescopic manner to vary the over-all length of the 65 device, whereby the jack may be applied to windows of different heights and be made to engage with both the bottom and top of the casing so that it is firmly secured in place. The portion 1 of the frame is provided with ratchet teeth 10 extending substantially throughout its length, these teeth being placed at the inner side of a recess 11, in which the bar 2 is guided and held.

The bar 2 has a pawl or dog 20 secured thereto, and held, by spring 21, into engagement with the ratchet teeth 10. Associated with the pawl 20 is a lever 22 by which the bar 2 may be raised so as to engage with the upper side of the window casing. The main 70 75 part 1 of the frame is provided with a slot 12, at the back, through which the lever 22 projects.

At the other side of the main part of the frame 1 is another recess, 13, which recess is also provided with a slot 14 for the projection of a locking dog 15. The inner surface of the recess 13 is also provided with a series of teeth, these forming a rack which is suitable for engagement by 80 a pinion, as 3, which is journaled in a slide 4, said slide fitting in and being guided by the channel 13 of the frame.

The axis 30 of the pinion 3 extends through slots 18 and 16, at opposite sides 95 of the frame, and at one end has a small crank, as 31, by which it may be turned. Upon its opposite end it has a slide block 32, and also has pivotally connected therewith the dog 5, which is shown separately 100 in Fig. 4. This dog 5 is pivoted so that it may be turned to present its window engaging end 50 for use in either raising or lowering the window.

This dog device 5 is shown as composed of two parts, 51 and 52, which are pivoted together at 53. At the point 54 the lower portion 52 is provided with a cross bar, or

other means, engaging the back side of the part 51 so as to prevent swinging in one direction beyond the position shown in Fig. 4.

- 5 The outer part 52 of this dog has an edge 50 provided preferably with a side tooth at its outer end and of a size and shape adapted to enter the side finger recess which is usually provided at the bottom of a window. In such windows as have a metal finger hold secured to their bottom bar and projecting outwardly, this may engage such finger hold.

10 It is evident that if the pinion 3 be turned by using the crank 31, the slide 4, in which it is journaled, will be made to move in its guideway up or down the bar 1, and if the dog 5 is engaged with the window, the window will be raised or lowered, as the case 15 may be.

15 In order to secure the jack in place by a secure bearing against both the window sill and the top of the casing, I have provided means by which a slight, and yet a powerful 20 adjustment of these two parts may be secured for the major adjustment, as by sliding the bar 2 outwardly.

25 By using the dog 20 and the ratchet teeth 10 this adjustment of the combined length 30 of the two parts can only be made in units of the length of the teeth. This will not at all times secure a firm engagement with the window casing. I, therefore, pivot the dog 20 upon an eccentric bearing 60 which is carried by the lever 22. This lever 22 is, however, journaled in the bar 2 by means of pivot pins 6, which are placed eccentric with the circle 60. Upon sliding the bar 2 up until it engages with the top of the window 35 casing, the dog 20 is engaged with the uppermost tooth with which it may be made to engage.

40 To secure a firmer engagement, the lever 22 is then swung downward. The eccentric 45 acts upon the dog 20 to force the bar 2 upward and to increase slightly the over-all 50 length of the two parts. In this manner the device is caused to be firmly secured in place between the top and bottom portions of the window casing.

55 The device shown in Figs. 6, 7, 8 and 9, is somewhat different in construction. This employs a bar 7 which is provided with rack teeth 70 upon one edge, and preferably with 55 a foot 71 in order to provide somewhat

larger surface for engagement with the window sill. A slide 8 embraces this bar.

This slide may be made by a single piece of sheet metal bent into the shapes shown. This is provided with two projecting ears 60 80 in which is journaled the pivot axis of the pinion 3. This pinion is similar in construction and its manner of operation with the pinion, as heretofore described.

The plate from which the slide 8 is made 65 may have ears, as 81, and 82, bent so as to overlap the toothed edge of the bar 7. It also has an ear 83, cut from its lower portion and projecting to one side, and serving as a finger with which the window is engaged. 70

The operation of this device is the same as the other device. The finger 83 is lowered to the point where it may be engaged with the finger hold at the bottom of the window. The crank 31 is then turned so as to cause 75 the pinion to move up along the rack teeth 70, carrying with it the slide 8. This slide being engaged with the window through the finger 83 carries the window with it.

What I claim as my invention is:

1. A window lifting jack comprising two bars adjustable lengthwise each other, means for locking said bars in adjusted relation, one of said bars having rack teeth, a slide mounted to move lengthwise of the rack bar, 80 a pinion journaled in said slide and meshing with the rack bar, means for turning the pinion, and a window-engaging dog carried by the slide.

2. A window lifting jack comprising a 90 rack bar, a slide guided lengthwise of and by said rack bar, a pinion journaled in said slide and meshing with the teeth of the rack bar, means for turning the pinion, and a window-engaging dog pivoted upon the 95 slide by an axis substantially parallel with the axis of the pinion.

3. A window lifting jack comprising two bars adjustable lengthwise each other, means for locking said bars in adjusted relation, 100 one of said bars having rack teeth, a slide mounted to move lengthwise of the rack bar, a retaining dog carried by the slide and engaging the rack teeth, a pinion journaled in said slide and meshing with the rack bar, 105 means for turning the pinion, and a window-engaging dog pivoted upon the slide.

Signed at Seattle, Washington, this 28d day of December, 1918.

EMMANUEL W. ROBINSON.
